US00D934782S

(12) **United States Design Patent** (10) **Patent No.:** **US D934,782 S**
(45) **Date of Patent:** **** Nov. 2, 2021**

(54) **PASSENGER SEATING APPARATUS**

(71) Applicant: **Rockwell Collins, Inc.**, Cedar Rapids, IA (US)

(72) Inventors: **Jaan Lin**, Winston-Salem, NC (US); **Dan Udriste**, Winston-Salem, NC (US); **Stephen A. Puglisi**, Greensboro, NC (US); **Ryan J. Suhre**, Winston-Salem, NC (US)

(73) Assignee: **Rockwell Collins, Inc.**, Cedar Rapids, IA (US)

(**) Term: **15 Years**

(21) Appl. No.: **29/775,204**

(22) Filed: **Mar. 22, 2021**

(57) **CLAIM**

The ornamental design for a passenger seating apparatus, as shown and described.

DESCRIPTION

FIG. 1 is a front perspective view of a passenger seating apparatus;

FIG. 2 is a front elevation view of the passenger seating apparatus of FIG. 1;

FIG. 3 is a top plan view of the passenger seating apparatus of FIG. 1;

FIG. 4 is a bottom plan view of the passenger seating apparatus of FIG. 1;

FIG. 5 is a right side elevation view of the passenger seating apparatus of FIG. 1;

FIG. 6 is a left side elevation view of the passenger seating apparatus of FIG. 1;

FIG. 7 is a rear elevation view of the passenger seating apparatus of FIG. 1; and,

FIG. 8 is a rear perspective view of the passenger seating apparatus of FIG. 1.

Portions of FIGS. 1 through 8 are shown in broken lines illustrating portions of the article of manufacture that form no part of the claimed design.

1 Claim, 8 Drawing Sheets
